UNITED STATES PATENT OFFICE

2,634,992

KNOB RETAINING DEVICE

Thomas F. Nelson, Stratford, Conn., assignor to
General Electric Company, a corporation of
New York

Application January 23, 1951, Serial No. 207,377

1 Claim. (Cl. 287—53)

1

My invention relates to knob retaining devices and has as an important object the provision of improved means for holding a knob-like member in a predetermined position on a shaft.

A further object of my invention is to provide a retaining device which is simple in principle and construction, being more easily and economically effected than previous devices, such as set screws engaging threaded holes in a shaft and member to be retained thereto.

A further object of my invention is to provide a retaining device which affords slideable adjustment of the position of a member retained upon a shaft.

A still further object of my invention is to provide a shear safety device to prevent torques greater than a given torque from being transmitted from a member on a shaft to the shaft.

In carrying out my invention in one embodiment thereof, a knob is held in a predetermined position upon a shaft by a spring clip formed from wire to have an essentially V-shaped center portion and to have two leg portions extending therefrom in a plane substantially at right angles to the plane of the center portion. The leg portions are terminated in end sections bent back toward the center portion to lie at an acute angle with respect to the leg portions. The leg portions are forced into slots in the knob so that the center portion of the spring clip is in frictional engagement with the shaft.

While my invention will be described as applied to retaining a knob on a shaft, it is to be understood that it is not limited to such application, as the disclosure in this respect is merely illustrative for purposes of explaining the inventive concept.

The features of my invention which I believe to be novel are set forth with particularity in the appended claim. My invention itself, however, both as to its organization and method of operation together with further objects and advantages thereof, may best be understood by reference to the following description taken in connection with the accompanying drawing, in which Fig. 1 is a perspective view of a preferred form of the spring clip of my invention; Fig. 2 is an end view of a knob, spring clip, and shaft, which is shown in section, constructed and held together in accordance with one embodiment of my invention; Fig. 3 is the same as Fig. 2 except that it illustrates a second embodiment of my invention; Fig. 4 is the same as Fig. 2 except that it illustrates a third embodiment of my invention; and Fig. 5 is a sectional side view of Fig. 4

2

taken along line 5—5 illustrating the engagement, common to Figs. 2, 3 and 4, of the spring clip with the knob.

Referring to the drawing, a spring clip 1 is provided with a center portion 1a which is preferably in the shape of a V, or a truncated V; and also with two leg portions 1b and 1c, extending in a plane substantially at right angles to the plane of the center portion 1a, and terminated by two end sections 1d and 1e which are bent back, toward center portion 1a, to lie at an acute angle with respect to portions 1b and 1c respectively. Clip 1 is used to hold a member, such as a knob 2, in a predetermined position on a shaft means, such as a cylindrical shaft 3. Knob 2 is provided with a recess 4, shaped substantially to conform to the shape of the shaft it is to receive, and also with two anchoring recesses, such as the rectangular recesses 5 and 6, disposed on opposite sides of recess 4 for receiving the leg portions of clip 1 as shown in Fig. 5. The width of recesses 5 and 6 must be such that when the leg portions 1b and 1c of clip 1 are inserted therein, end sections 1d and 1e are deformed slightly, thereby causing sections 1d and 1e to exert pressure on the sides of recesses 5 and 6. The material of which the spring clip 1 is formed should be somewhat harder than the material from which knob 2 is formed so that during an attempted withdrawal of clip 1 from its engagement in anchoring recesses 5 and 6, end sections 1d and 1e of the leg portions dig into the side of their respective anchoring recesses, tending to prevent withdrawal therefrom.

After the leg portions 1b and 1c of the clip 1 have been inserted in recesses 5 and 6, the center portion 1a lies partially over the entrance to recess 4 in knob 2. Thus, when shaft 3 is inserted into recess 4, center portion 1a is forced to the side of the entrance whereby leg portions 1b and 1c are moved toward end sections 1d and 1e and a spring pressure is exerted on the shaft 3 by portion 1a and on the sides of recesses 5 and 6 by sections 1d and 1e.

In Fig. 2 the cylindrical surface of shaft 3 is unaltered so that the knob 2 is retained on the shaft 3 by frictional forces between the cylindrical surface of shaft 3 and portion 1a of the clip 1. The maximum force against which knob 2 is retained on shaft 3 may be determined by the design of spring clip 1 and the degree of roughness given to the surface of shaft 3. Therefore, this embodiment of the invention is of particular value to retain a knob on a shaft against relatively small axial and circumferential

forces but at the same time allowing the knob to be slidably and rotatably adjusted in position relative to the shaft by slightly greater forces.

In Fig. 3, the shaft 3 is provided with two notches 7 and 7' in its surface, these notches being formed with substantially the same angle between them as the angle of the V in spring clip 1. Notches 7 and 7' may be of any width along the axis of shaft 3 greater than the diameter of the wire forming spring clip 1. Thus, if notches 7 and 7' are only slightly greater in width along the axis of shaft 3 than the diameter of the wire forming spring clip 1, center portion 1a fits snugly into notches 7 and 7', and the knob is firmly retained on the shaft against axial and circumferential forces. This is probably the most useful form of the embodiment shown in Fig. 3.

However, if notches 7 and 7' in Fig. 3 are made of greater width and extended along the axis of the shaft 3, the knob 2 will be firmly retained on the shaft 3 against circumferential forces but will be semi-firmly retained against axial forces, as in the embodiment of Fig. 2, whereby the knob 2 may be slidably adjusted to any axial position along the shaft within the axial limits of notches 7 and 7'.

Further, the circumferential frictional retaining force between spring and shaft in the embodiment of Fig. 3 may be determined by the design of the spring clip 1, the angle between notches 7 and 7', and the degree of roughness given to the surfaces of notches 7 and 7'. Therefore, my invention may be used as a shear safety device, limiting the maximum torque transmittable between knob 2 and shaft 3. If the circumferential force between the knob 2 and shaft 3 exceeds the designed circumferential frictional force, the knob will slip upon the shaft until such time that the two forces equalize, when the knob 2 will re-index at the same circumferential position on the shaft 3 and transmit the torque.

In Figs. 4 and 5 the shaft 3 is provided with an annular groove 8 into which the center portion 1a of the clip 1 fits under spring force so that the knob 2 is firmly retained upon the shaft 3 against axial forces but only semi-firmly against circumferential forces depending upon the design of the spring and the roughness of the sur-

face of groove 8. Thus, the embodiment shown by Figs. 4 and 5 is most useful when used on a shaft to be moved or pulled axially but which must not be loaded by too great of a circumferential torque.

While the present invention has been described by reference to particular embodiments thereof, it will be understood that numerous modifications may be made by those skilled in the art without actually departing from the invention. I, therefore, aim in the appended claim to cover all such equivalent variations as come within the true spirit and scope of the foregoing disclosure.

What I claim as new and desire to secure by Letters Patent of the United States is:

A retaining and indexing device comprising a cylindrical shaft having two notches in the periphery thereof extending circumferentially of the shaft, a knob having a cylindrical recess therein for receiving said shaft and having two anchoring recesses on opposite sides of said first mentioned recess, a spring wire clip having a V-shaped center portion, two leg portions extending from said center portion in planes substantially at right angles to the plane of said center portion, two end sections terminating said leg portions and each bent toward said center portion to lie at an acute angle with respect to its respective leg portion, said notches being located with respect to one another at an angle normal to the axis of the shaft substantially equal to the angle formed by said V-shaped center portion of said spring clip, said clip positioned with said leg portions thereof each disposed in a different one of said anchoring recesses and with said end section of each leg portion in frictional engagement with the side of its respective anchoring recess, said V-shaped portion of said spring engaging said shaft in said notches to retain said knob in a predetermined indexed position with respect to said shaft.

THOMAS F. NELSON.
